UNITED STATES PATENT OFFICE.

JOHN H. GREENWOOD AND WILLIAM H. COWELL, OF LOGAN, OHIO.

RAILWAY SWITCH-STAND.

SPECIFICATION forming part of Letters Patent No. 253,861, dated February 21, 1882.

Application filed January 3, 1882. (No model.)

To all whom it may concern:

Be it known that we, JOHN H. GREENWOOD and WILLIAM H. COWELL, of Logan, in the county of Hocking and State of Ohio, have 5 invented certain new and useful Improvements in Railway Switch-Stands; and we do hereby declare that the following is a full, clear, and exact description of the invention, which will enable others skilled in the art to which it applies to make and use the same, reference being had to the accompanying drawings, and to letters of reference marked thereon, which form a part of this specification.

Figure 1 is a perspective view of our improved switch-stand. Fig. 2 is a detail of the quadrant-hinge.

Similar letters in the figures indicate like parts.

Our invention consists in the peculiar construction of a railway switch-stand capable of use either at or on a one, two, or three throw switch by changing the position of a hinged arc or quadrant to which the switching-lever is fulcrumed, which arc may be raised to a vertical plane when in use, or lie horizontal upon the ground, out of the way of passing trains or persons, the switch-shifting mechanism being specially adapted and intended for confined and narrow spaces when the ordinary switch-stand could not be used, but capable of use in any situation where a switch may be needed, all as hereinafter more specifically set forth.

In the drawings, K represents the tie upon which the device stands. The plate H, which 35 supports the operative parts, is fastened to the tie by bolts or spikes. To this plate are attached the hinge-eyes C C, through which are passed pieces of pipe C' C', projecting inward far enough to form pintles for the eyes 40 of the quadrant G to turn upon. The quadrant turns upon these pintles through an arc of one hundred and eighty degrees, in order that after being used in a vertical position as the fulcrum of the lever F to throw the switch in either direction, it may be dropped upon the ground on either side of tie K, and be out of the way of passing trains or persons. When thus disposed of, it lies nearly parallel with the track and below the level of the rails.

50 The shifting-bar B, passing through the hollow pintles C' C', is a straight sliding bar connected with the rail either directly or by the joint A, as preferred, or may be pivoted to the end of the tie-rod M. This bar B has in 55 the middle, between the hinges C C, a swivel-

joint, O, upon which the lever F and the strap E, to which it is pivoted at p, turn when the quadrant is moved from side to side. This swivel is composed of a sleeve, P, fixed on bar B, and having a groove or recess in which the strap E is received and turns. To this strap the lever F is pivoted at p. Said lever is also provided with a slot, L, so that when it is moved back and forth to throw the switch it can slide up and down on a pin, N, projecting from the quadrant G, and not tend to raise and bind the rod B. This slot might with the same effect be placed near the lower end of lever F, where it is pivoted to strap E.

When the lever F is thrown for the middle or main line, as in Fig. 1, and then dropped on the ground on either side of tie K, the strap E, to which it is attached, falls into one of the notches D² and holds the rail in the desired position. The operation for the other positions is similar and too obvious to need description.

Having thus fully described our invention, what we claim, and desire to secure by Letters Patent, is—

1. The described combined three-throw hinged railway switch-stand, the quadrant and lever of which are hinged to the base, so that after use in an upright position they can be dropped upon the ground on either side of the tie on which they are supported, so as to be out of the way of passing trains or persons, all substantially as specified.

2. The combination of the plate H, hinges C, hollow pintles C' C', hinged quadrant G, lever F, swivel O, strap E, racks D, and rod B, in the manner and for the purposes set forth.

3. In a railway switch-stand, the combination of the switching-lever with a hinged quadrant capable of being folded down upon the ground on either side, so that the lever and arc will be out of the way, as described.

4. In a railway switch-stand, the locking device consisting of the combination of the rod B, sleeve P, strap E, and racks D', in the manner and for the purpose stated.

In testimony that we claim the foregoing as our own invention we affix our signatures in presence of two witnesses.

JOHN H. GREENWOOD.
WILLIAM H. COWELL.
